UNITED STATES PATENT OFFICE.

LEO A. POVASKI, OF SAULT STE. MARIE, MICHIGAN.

PRIMING-CUP FOR INTERNAL-COMBUSTION ENGINES.

1,176,851.

Specification of Letters Patent. Patented Mar. 28, 1916.

Application filed July 22, 1915. Serial No. 41,327.

To all whom it may concern:

Be it known that I, LEO A. POVASKI, a citizen of the United States, residing at Sault Ste. Marie, in the county of Chippewa and State of Michigan, have invented certain new and useful Improvements in Priming-Cups for Internal-Combustion Engines, of which the following is a specification.

The present invention relates to a priming cup for internal combustion engines, and has for its object to provide a device of this character which embodies novel features of construction whereby the engine may be quickly primed at any time without the necessity of manually manipulating a valve.

Further objects of the invention are to provide a priming cup which is comparatively simple and inexpensive in its construction, which can be used interchangeably with the ordinary priming cups, which admits of the engine being quickly primed from an ordinary gasoline can, and which is so constructed as to prevent accumulations of dust or carbon upon the valve seat.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a side elevation of a priming cup for internal combustion engines, constructed in accordance with the invention. Fig. 2 is a vertical sectional view through the same, a gasoline can, and the manner of opening the valve therewith, being shown in dotted lines.

Corresponding and like parts are referred to in the following description and indicated in all the views of the drawings by the same reference characters.

Specifically describing the present embodiment of the invention, the reference character 1 designates a tubular stock which has one end thereof threaded at 2 so as to be screwed into the usual opening of the cylinder head, and is closed at the opposite end. An offset barrel 3 is provided upon one side of the tubular stock 1 and is preferably integral therewith. The bore of the barrel is shown as parallel to the opening of the tubular stock 1 and is closed at its lower

end by a removable plug 4. A by-pass 5 establishes communication between the upper end of the tubular stock 1 and the upper end of the barrel 3, the end of the by-pass being normally closed by a check valve 6 which is slidably mounted within the barrel, and normally closes an inlet opening 7 in the upper end thereof. A cup 8 projects upwardly from the barrel 3 and communicates at the bottom thereof with the inlet opening 7, so that when the valve is open, gasoline within the cup will flow through the tubular stock 1 into the engine. The upper end of the valve 6 is formed with a stem 9 which normally projects upwardly through the inlet opening 7, the extremity of the stem being concave at 9^a so as to be easily engaged by the nozzle of a gasoline can A. At the base of the stem 9 the valve 6 is formed with a tapered or frusto-conical shoulder 6^a which engages a correspondingly shaped valve seat 10 at the upper end of the barrel 3. Interposed between the lower end of the valve 6 and the removable plug 4 is a coil spring 11 which normally holds the valve yieldably against its seat, the end of the valve then closing the inlet opening 7, while the side thereof extends across and closes the by-pass 5.

In order to prime the engine, the nozzle of the gasoline can A is placed in engagement with the concave seat 9^a at the extremity of the valve stem 9 and the valve 6 pushed downwardly against the action of the spring 11, until the inlet opening 7 is opened and the valve moved to a point beyond the by-pass 5. Gasoline from the can A will then flow readily through the by-pass 5 into the tubular stock 1, and thence into the engine cylinder. As soon as the gasoline can is removed the spring 11 will again force the valve 6 into a closed position, and there is no need for manually manipulating the valve or paying any special attention thereto. When the engine is in operation neither the suction nor the explosions have any effect on the valve seat, and there is no opportunity for carbon or other foreign matter to accumulate upon the valve seat. Each time the engine is primed the charge of gasoline flows around the valve seat and the tapered end of the valve so as to thoroughly cleanse the same, and an accurate and tight seating of the valve is thereby assured at all times. Should it be necessary at any time to remove the valve,

this can be readily accomplished by first unscrewing the plug 4. In drilling the by-pass 5 an opening is formed in one side of the stock 1, and this opening is shown as 5 permanently closed by a plug 12.

Having thus described the invention, what I claim as new and desire to secure by Letters Patent, is:—

1. A priming cup for internal combustion engines, including a tubular stock, a barrel 10 having an inlet opening in one end thereof and communicating with the tubular stock through a by-pass at one side thereof, and a spring seated valve slidably mounted within 15 in the barrel, one end of the valve closing the inlet opening of the barrel, while the by-pass is closed by one side of the valve.
2. A priming cup for internal combustion engines, including a tubular stock, a barrel 20 having an inlet opening in one end thereof and communicating with the tubular stock through a lateral by-pass, a tapered valve seat being provided around the inlet opening, and a spring seated slide valve mounted 25 within the barrel, one end of the slide valve being tapered for coöperation with the valve seat to close the inlet opening, and the sides of the valve serving to close the by-pass.
3. A priming cup for internal combustion engines, including a tubular stock, a barrel 30 having an inlet opening at one end thereof and communicating with the tubular stock through a lateral by-pass, and a spring seated valve slidably mounted within the barrel, said valve having a stem at one end thereof which normally projects through the 35 inlet opening and the sides of the valve serving to close the by-pass.
4. A priming cup for internal combustion engines, including a tubular stock, a barrel 40 having an inlet opening at one end thereof and communicating with the tubular stock through a lateral by-pass, a tapered valve seat being provided which surrounds the in- 45

let opening, and a spring seated valve slidably mounted within the barrel, one end of the valve being formed with a stem to enter the inlet opening and a tapered portion for coöperation with the valve seat, while the 50 by-pass is closed by the sides of the valve.

5. A priming cup for internal combustion engines, including a tubular stock, an offset barrel arranged at one side of the tubular stock and parallel thereto, a by-pass being 55 provided which establishes communication between the barrel and the tubular stock, and one end of the barrel being formed with an inlet opening and a valve seat surrounding the same, and a spring seated valve slidably mounted within the barrel, one end of the valve being constructed for coöperation with the valve seat to close the inlet opening while the sides of the valve serve to close the by-pass.

6. A priming cup for internal combustion engines, including a tubular stock, an offset barrel parallel to the tubular stock and arranged at one side thereof, a lateral by-pass being provided which establishes communication between the barrel and the tubular stock, one end of the barrel being formed with an inlet opening and a tapered valve seat surrounding the same, a valve slidably mounted within the barrel and having one 70 end thereof tapered for coöperation with the valve seat, while the sides of the valve serve to close the by-pass, the tapered end of the valve being formed with a stem which passes through the inlet opening for engagement with the nozzle of a gasolene can, and a spring holding the valve yieldably upon its seat.

In testimony whereof I affix my signature in the presence of two witnesses.

LEO A. POVASKI.
